CONTROL AND CHANGE MAKER FOR
VENDING MACHINES

Marvin G. Nelsen, Skokie, Ill., assignor to Guardian Electric Manufacturing Co., Chicago, Ill., a corporation of Illinois

Application April 9, 1949, Serial No. 86,579

4 Claims. (Cl. 194—10)

1

This invention relates to a control and change maker for vending apparatus.

It is an object of the invention to provide an improved control for apparatus which vends services or goods.

It is also an object of the invention to provide an improved change maker for vending apparatus.

It is an additional object of the invention to prevent completion of a portion of a change making cycle if a switch, operated by a coin of a larger denomination than that represented by a single unit (such as a nickel), remains closed for any reason after it should have opened; and, furthermore, in such a case, to permit vending by the utilization of coins or checks representing a single denomination unit.

It is also an object of the invention to prevent jackpotting of either change, goods, or services.

It is an important object of the invention to prevent jackpotting of a change magazine in a change maker to prevent continued pay-out of change by the utilization of only one coin of a larger denomination than a single unit.

It is also an object of the invention to insure delivery of the goods or services desired, together with the proper change, if any, when the mechanism is operating properly.

It is a further object of the invention to prevent the further delivery of goods, or services, or change, by continued cycling of the vending apparatus, or by the insertion of a coin or check of larger denomination than one unit, if switch means operated by a coin or check of a larger denomination than one unit remains in an improper position at the end of a vending cycle; also, to return such larger denomination coins or checks, which are thereafter utilized in the mechanism until such switch means returns to its proper position.

It is an additional object of the invention to prevent the delivery of goods, services, or change by continued cycling of the vending apparatus, or by the insertion of a coin of any denomination, if a coin or check of the denomination corresponding to a single unit maintains a corresponding coin switch in an improper position.

It is a further object of the invention to block or return coins of a larger denomination than a single unit if the magazine of the coin changer contains less than a predetermined number of coins or checks; and also to permit a vending operation by a coin of single unit denomination when the magazine contains less than said predetermined number of coins or checks.

2

With these and other objects in view, the invention consists in the construction, arrangement and combination of the various parts of my device whereby the objects contemplated are attained, as hereinafter more fully set forth, pointed out in the claims and illustrated in the accompanying drawings, wherein:

Figure 1 is a front elevational view of the change maker unit including blocking relays and combination vending control and change making relays;

Figure 2 is a partial sectional view of the apparatus taken on the line 2—2 of Figure 1;

Figure 3 is a partial sectional view of the payout solenoid coin magazine and associated apparatus;

Figure 4 is a partial sectional view of the apparatus taken on line 4—4 of Figure 1;

Figure 5 is a partial sectional view of the apparatus taken on the line 5—5 of Figure 1;

Figure 6 is a view of the motor-operated cams and one of the switches operated thereby;

Figure 7 is a partial sectional view of the coin magazine taken on the line 7—7 of Figure 3;

Figure 8 is a partial sectional view of the coin operated switches taken on the line 8—8 of Figure 4;

Figure 9 is a wiring diagram showing the parts of the vending and change making mechanism diagrammatically;

Figure 10 is a diagrammatic view of the coin or check chutes with the blocking relays and return chute also shown diagrammatically;

Figure 11 is a diagrammatic view of one of the motor operated cams and the switch associated therewith, with the parts in a position they assume at one part of the cycle;

Figure 12 is a view similar to Figure 11 at another part of the cycle;

Figure 13 is a view similar to Figures 11 and 12, at another part of the cycle; and

Figure 14 is a detailed view of the latching relay for rendering the apparatus completely inoperative under certain conditions.

Referring specifically to the drawings for a detailed description of the invention and particularly to Figure 1, numeral 10 designates an open front box, preferably of metal, upon which certain component elements of the present invention are mounted. The box 10 is preferably mounted vertically and includes a bottom wall 11, a top wall 12 and an intermediate partition 13. The base of the box 10 is designated by the numeral 9.

A two pole, double throw drain switch 14 is mounted on the top wall 12 for continuous drain-

ing of the change in the mechanism when desired. The invention is described as applying to nickels, dimes and quarters and to the vending of a nickel article, although it is obvious that other coins or checks may be utilized and articles of different prices may be vended. The nickels are, therefore, referred to as coins of "unit denomination," while the other coins are sometimes referred to as coins of "multiple unit" denomination. Nickels are the coins given in change in the device as described.

Referring to Figures 1 and 9, a 10¢ or dime relay 15 and a 25¢ or quarter relay 16 are mounted on the base 9. A nickel block relay and a dime and quarter block relay, generally indicated by the numerals 17 and 18, respectively, are mounted on base 9. A motor 19 is mounted on a bracket 20 which is in turn also mounted on base 9. A change pay-out solenoid 21 and a change magazine 24 are secured to the bottom wall 11 of box 10. A pair of cam operated switches 22 and 23 are mounted on base 9.

As shown in Figure 9, other components which are part of the vending machine control, as distinguished from the change maker, comprise a vend relay 25, a vend motor 26, an anti-jack-potting relay 27, a "5¢ only" lamp 28, an "empty" lamp 29, a "limit" switch 31 and an "empty" switch 32.

A standard coin chute and slug ejector, shown diagrammatically at 39 in Figures 5 and 10, is removably secured to the box 10 by any suitable means (not shown). Nickel, dime and quarter operated switches indicated at 33, 35 and 37, respectively, are disposed at the proper outlet from the coin chutes, as shown in Figure 4 and diagrammatically shown in Figure 9. The nickel, dime and quarter chutes are shown at 34, 36 and 38, respectively. A single inlet for coins of all three denominations is shown at 41, and the coins are directed into the proper chute by selector mechanism (not shown), if the coin is acceptable. A return coin chute is shown at 42 and coins which are not acceptable for any reason are directed to the return chute by mechanism hereinafter described. The selector mechanism and coin chutes are so positioned that the nickel blocking relay and the dime and quarter blocking relay will be effective to prevent operation of the coin switches 33, 35 and 37, or some of them, under certain conditions, as will become apparent as the description proceeds.

Referring to Figures 1 and 9, the drain switch 14 is operated by a manually movable switch operating member 43, which extends above the top of wall 12 of the box 10. The switch 14 comprises a pair of movable switch arms 44 and two pairs of fixed contacts 46 and 47. The diagram, Figure 9, shows all parts and switches in the position wherein a cycle of operation may be initiated by the insertion of a nickel, dime or quarter.

Referring again in Figures 1 and 9, the dime relay 15 includes a coil 48 which is adapted to attract an armature 49 when energized. Normally, the armature is maintained in the unattracted position, as shown in Figure 1, by a spring 51. The armature 49 is adapted to operate a plurality of switch arms which are assembled in a switch generally indicated at 52.

The dime relay 15 operates movable contact arms 53, 54, 55. Associated with the switch 52 are relatively fixed contact arms 56, 57, 58, 59. Throughout the description of the contact arms of the switches, it is to be understood that the arms are formed of flexible metal and bend or

return to their initial position shown in Figure 9 due to the inherent resiliency thereof when not biased to another position by some mechanical movement. A contact 61 is provided on contact arm 56 and is adapted to engage with a contact 62 on switch arm 53. A contact 63 is provided on contact arm 57 and is adapted to engage with a contact 64 on movable contact arm 54. A contact 65 is provided on contact arm 58 and is adapted to engage with a contact 66 on movable contact arm 55. A contact 67 on movable contact arm 55 is adapted to engage with a contact 68 on contact arm 59. A rigid member 60 engages with the armature 49 and the movable contact arms 53, 54, 55 in order to impart movement thereto.

The quarter relay 16 includes a coil 69 which is adapted to attract an armature 70 thereto. The armature 70 is normally maintained in the unattracted position by a spring 71. The armature 70 is adapted to operate a switch, generally indicated at 72. The switch includes movable contact arms 73, 74, 75 and 76. Also, associated with the switch are relatively fixed contact arms 77, 78, 79, 81 and 82. The movable contact arms are secured to the armature 70 by a member 80 which imparts movement to the contact arms when the armature is moved.

A contact 83 is secured to the contact arm 71 and is adapted to engage with a contact 84 on movable switch arm 73. A contact 85 on switch arm 78 is adapted to engage with a contact 86 on movable switch arm 74. A contact 87 on switch arm 79 is adapted to engage with a contact 88 on movable switch arm 75. A contact 89 on movable switch arm 75 is adapted to engage with a contact 91 on switch arm 81. A contact 92 on movable switch arm 76 is adapted to engage with a contact 93 on switch arm 82.

The five-cent block relay 17 includes a coil 94 which is adapted to operate an armature 95 which is hinged at 96. A spring 90 tends to maintain the armature in the unattracted position. The armature 95 has a bracket 97 secured thereto terminating in a blocking finger 100.

The dime and quarter blocking relay 18 includes a coil 98 which is adapted to move an armature 99 which is hinged at 101. A spring similar to the spring 90 is adapted to normally maintain the armature in the unattracted position. The armature 99 has a bracket 102 secured thereto and dime and quarter blocking fingers 103 and 104 respectively are secured at the extremities of the bracket 102. The blocking fingers 100, 103 and 104 extend through openings 100a, 103a and 104a in the coin chutes 34, 36 and 38, respectively, as best shown in Figure 10. The return chute 42 communicates with an inclined open top coin runway 42a, and when any one of the blocking fingers 100, 103 and 104 are in the blocking position, corresponding coins are deflected into runway 42a and returned through return chute 42.

A switch generally indicated at 105 is also operated by the armature 99 and the dime and quarter block relay 18. The switch 105 includes a movable contact arm 106 and a relatively fixed contact arm 107. The movable contact arm 106 has a contact 108 thereon adapted to engage with a contact 109 on the contact arm 107. The contacts 108 and 109 are closed when the dime and quarter blocking relay 18 is deenergized and are open when it is energized.

The motor 19 which is mounted on the bracket 20 includes a coil 111 and a metallic stator 112. The motor 19 may be of the well-known shaded

pole type. The motor 19 includes a rotor 113 which is adapted to rotate a shaft 114 through a gear chain 117, when power is applied to the motor. The shaft 114 in turn rotates a cam 115 and a cam 116 for actuating switches 22 and 23, respectively.

The cam 115 is provided with a notch 118 and with a smooth high surface 119. It is also formed with a raised portion 120. The cam 115 is adapted to move a movable switch arm 121 and a movable switch arm 124, which are connected together by a member 110 on switch 22. The movable arm 121 has a V-shaped projection 122 which is adapted to either ride on the surfaces 119 and 120 of the cam 115 or to be positioned in the notch 118 to operate the switch arms 121 and 124 in a manner to be described.

Also associated with switch 22 are contact arms 123, 125, 126. A contact 127 on movable contact arm 121 is adapted to engage with a contact 128 on contact arm 123. A contact 129 on contact arm 126 is adapted to engage with a contact 131 on contact arm 123. A contact 132 on contact arm 125 is adapted to engage with a contact 133 on contact arm 124.

The cam 116 is provided with a smooth lower surface 134 and with three raised portions 135 and a fourth raised portion 135a which is higher than portions 135. The portions 135 are adapted to move movable switch arm 136 on switch 23. The portion 135a is adapted to move both switch arms 136 and 138. The movable switch arm 136 is provided with a V-shaped projection 137 which either rides on the smooth surface 134 of the cam 116 or is raised by the projections or cam surfaces 135 thereof.

The switch 23 includes a switch arm 139. The movable switch arm 136 has a contact 141 thereon adapted to engage with a contact 142 on switch arm 138. A contact 143 on switch arm 138 is adapted to engage with a contact 144 on switch arm 139.

Referring now to Figures 1, 3, 7 and 9, the coin magazine 24 normally has a plurality of nickels therein, shown at 145. A switch 140 is associated with the coin magazine to insure that sufficient coins are present therein for giving change for at least one quarter when a coin of such denomination is used. The switch 140 includes a movable member 146 which projects through an opening 150 in the side of the coin magazine 24. The switch 140 also includes a switch arm 147 secured to the member 146 and a switch arm 148.

A contact 149 is secured to the switch arm 147 and is adapted to engage a contact 151 on switch arm 148 when sufficient coins 145 are contained in the magazine 24.

Referring to Figures 1, 3 and 9, the change payout mechanism 21 includes a coil 152, a laminated metal core 153, and a slidably armature 154. The armature 154 is connected to a plate 155 by means of an upright stud 160, which plate slides on the bottom 11 of the box 10. An ear 156 is secured to the stud 160 and a spring 157 is secured to the ear 156 and to a rigid bracket 158, which is in turn secured to the box 10. The spring 157 biases the armature 154 to its unattracted position. An aperture 159 is provided in the bottom of the magazine 24 so that coins may be released therefrom by gravity when the plate 155 is moved by armature 154. The plate 155 is adapted to eject one nickel at a time and drop it through an aperture 159a in the plate 11. The aperture 159a is not in alignment with aper-

ture 159 in the bottom of the magazine, so that only the nickel sliced off the bottom of the stack in magazine 24 will be delivered in order to make change.

Referring now to Figures 4, 8 and 9, the nickel coin switch 33 includes a movable contact arm 162 which is disposed in a position to be engaged by a nickel from nickel coin chute 34. The coin switches 33, 35 and 37 are shown to be of the type which are operated to close a switch momentarily upon the passage of a coin. However, the invention is not limited thereto but is also applicable to coin switches in which coins are released by mechanical means, such as cams, at a predetermined time, and the coin switch associated therewith is returned to the initial position at that time.

The nickel switch 33 has a finger 162 which will be struck by a nickel passing through the coin chute 34. The switch also includes a switch arm 163. A contact 164 on the movable switch arm 162 is adapted to engage with a contact 165 on the switch arm 163. The dime switch 35 includes a movable switch arm 166 to which is secured a finger 167 which is adapted to be struck by a dime as it passes through coin chute 36. The switch 35 also includes a contact arm 168 and a movable contact arm 166 has a contact 171 thereon adapted to engage with a contact 169 on contact arm 168.

The quarter switch 37 is shown in greater detail in Figure 8 and it is understood that all three of the coin switches are identical in construction. The quarter switch 37 includes a movable contact arm 172 and a relatively fixed contact arm 174. A finger 173 is adapted to be struck by a quarter when it passes through the chute 38. The movable contact arm 172 has a contact 175 thereon which is adapted to engage with a contact 176 on contact arm 174. The finger 173 is pivoted at 177 and is provided with a bell crank extension 178 having a pusher projection 179 thereon, so that, as the finger 173 is moved to the dotted line position, shown in Figure 8 of the drawings, the projection 179 engages the movable switch arm 172 and closes contacts 175, 176. The movable arm 172 is inherently resilient and as soon as the coin has passed by the finger 173, it swings the finger to the full line position shown in Figure 8 and contacts 175 and 176 open.

Referring now to Figure 9 for a detailed description of a portion of the vending apparatus, the vend relay 25 includes a coil 191 which operates an armature 192. The armature 192 is normally maintained in its unattracted position by a spring (not shown) and is only moved to the attracted position each time a coin is inserted in the coin chutes. The armature 192 operates a switch generally indicated by the numeral 190 which includes movable contact arms 193 and 194 and fixed contact arms 195, 196 and 197. The movable contact arm 193 has a contact 198 thereon which is adapted to engage with a contact 199 on contact arm 195. A contact 201 is provided on contact arm 196 and is adapted to engage with a contact 202 on contact arm 194. A contact 203 on contact arm 194 is adapted to engage a contact 204 on contact arm 197.

The "limit" switch 31 includes a movable contact arm 205 and two relatively fixed contact arms 206, 207. A contact 208 is provided on contact arm 207 and is adapted to engage with a contact 211 on contact arm 205. A contact 212 on contact arm 205 is adapted to engage with a contact 213 on contact arm 206.

The "empty" switch 32 includes a movable

contact arm 214 and fixed contact arms 215 and 216. The contact arm 215 has a contact 217 thereon adapted to engage with a contact 218 on contact arm 214. A contact 219 on contact arm 214 is adapted to engage with a contact 221 on contact arm 216.

The "anti-jackpotting" relay 27, shown in Figures 9 and 14, is a latch type relay and includes a solenoid 222 and an armature 223. The relay 27 operates a switch generally indicated at 220 which includes a movable switch arm 224 and relatively fixed switch arms 225, 226. The switch arm 225 is provided with a contact 227 which is adapted to engage with a contact 228 on movable contact arm 224. A contact 229 is provided on contact arm 224 which is adapted to engage with a contact 231 on contact arm 226.

The switch 220 is normally maintained in the position shown in Figure 9 by a latch generally indicated at 232, as shown in Figure 14. A manually movable arm 233 is pivoted at 234 and is biased in a clockwise direction by a spring 235. When the coil 222 is energized, it attracts armature 223 and latch 232 is unlatched. Contacts 225, 227, therefore, open and contacts 229, 231 close. The contacts remain in such position until the arm 233 is manually raised to re-latch latch 232.

General operation

As best disclosed in Figure 9, power is supplied to the circuit through lines L1 and L2. Before the mechanism is in condition for operation, power must be supplied to lines L1 and L2 and the latch 232 of the anti-jackpotting relay must be in the latched position, so that contacts 227, 228 are closed and contacts 229, 231 are open. It is again noted that throughout the description, the switch arms are of sufficient resiliency to position the switches with the proper contacts opened and closed when not biased to some other position by a mechanism such as a solenoid, a cam, or the like.

With the power on, the contacts 227, 228 closed and sufficient coins 145 in the magazine 24 to close contacts 149, 151, the block relays 17 and 18 will be energized to withdraw the blocking fingers 100, 103, 104, sufficiently from the coin chutes 34, 36 and 38, that coins may pass therethrough and strike the fingers 162, 167 and 173 of the nickel, dime and quarter switches 33, 35 and 37. The contacts 217, 218 of the empty switch must also be closed and this is accomplished by the presence of merchandise in the vending machine.

Furthermore, the contacts 208, 211 of the limit switch 31 must be closed and this is accomplished by the inherent resiliency of the switch at the end of a vending cycle. A cam 210, for example, may be provided to close the limit switch contacts 208, 211 and open contacts 212, 213 at the end of each vending cycle.

When the system is in the above condition, the following circuits are established to energize the blocking relays 17 and 18; through line L1, conductor 238, through closed contacts 227, 228 of the anti-jackpotting switch, through conductors 252, 253, through closed contacts 217, 218 of the empty switch, through conductors 254 and 255, closed contacts 208, 211 of the limit switch, through conductor 247, closed contacts 201, 202 of the vending relay, through conductors 248, 256 and 257, through coil 94 of blocking relay 17, through conductors 258, 244 to line L2, thus energizing blocking relay 17. It will be noted that at the junction point marked "A" on Figure 9, L1 power exists, as long as the vending relay 25,

5 limit switch 31, empty switch 32 and anti-jackpotting relay 27, have their contacts in the position shown in Figure 9. It will, therefore, be unnecessary to again trace through these circuits if the conditions are as above.

In order to energize block relay 18, power from the point "A" passes through conductor 256, through closed contacts 83 and 84 of the quarter relay 16, through closed contacts 149, 151 of the coin magazine switch 140, through conductor 243, to the coil 98 of relay 18 and through the conductors 242, 244 to line L2, thus energizing the block relay 18. It is to be noted that the block relay 18 when energized opens contacts 108, 109 of switch 105. It is obvious that no power may be supplied through the "five cent only" lamp 28, as long as block relay 18 is energized and contacts 108, 109 are open. The purpose of the "five cent only" lamp will be described in more detail hereinafter.

Nickel operation

Assuming the contacts to be in the positions shown in Figure 9, and the block relays 17 and 18 energized, if a nickel is placed in the slot 41 of the mechanism 39 and it is a proper coin, it will pass through the chute 34 and strike the finger 162 to momentarily close contacts 164, 165. The following circuits are thereupon established to operate the vend motor one cycle and to vend one article of merchandise; first, the vend relay 25 is energized by a circuit from line L1 through conductor 238, closed contacts 227, 228 of anti-jackpotting relay 27, through conductors 252, 253, through closed contacts 217, 218 of the empty switch, through conductors 254, 246, through closed contacts 164, 165 of the nickel coin switch 33, through conductor 259, through the coil 191 of the vend relay 25, through conductors 261, 262 and 244 to line L2, thus energizing vend relay 25.

Attention is also directed to the fact that with the switch contacts of the vend relay 25 the empty switch 32 and the anti-jackpotting relay 27 in the positions shown in Figure 9, that L1 power will always exist at point "B." Power from the line L2 will always exist at point "C," regardless of the condition of any of the remainder of the apparatus, as long as there is power supply to the circuit.

Closing of contacts 203, 204 establishes a holding circuit for the vend relay 25 as follows; from line L1 through the conductor 238, closed contacts 227, 228 of the anti-jackpotting relay, through conductor 352, closed contacts 217, 218 of the empty switch, conductors 254, 255, through closed contacts 208, 211 of the limit switch, through the conductor 247, closed contacts 203, 204 of the vend relay, through conductor 263, through the vend relay coil 191, conductors 261, 262 to point "C" and back to line L2 through conductor 244.

Power is thereupon supplied to the vend motor 26 from line L1 through conductor 238, contacts 227, 228 of the anti-jackpotting relay 27, conductor 252, through closed contacts 198, 199 of the vend relay 25, through conductor 259, through the vend motor 26, through conductor 262 to point "C" (line L2). The vend motor 26, therefore, will operate and will, for example, eject a package by suitable standard mechanism. The vend motor 26, as it completes its cycle, will rotate cam 210 to operate the limit switch 31 after the package is delivered, thus momentarily opening contacts 208, 211 and momentarily closing contacts 212, 213. The purpose of closing contacts 212, 213 will be explained hereinafter, but

it is obvious that opening of the contacts 208, 211 immediately breaks the holding circuit through contacts 203, 204 of the vend relay 25 and the vend relay 25 is deenergized so that the motor circuit to the contacts 198, 199 is broken and the motor 26 is stopped. After the supply of energy is discontinued to vend motor 26, it will coast a distance sufficient to close contacts 208, 211 and open contacts 212, 213.

Dime operation

Assuming that the parts are in the position shown in Figure 9 and the block relays 17 and 18 are energized so that the blocking fingers 100, 103, 104 are withdrawn from the coin chutes; when a dime is inserted in the coin chute 36 the following circuits are established to operate the cam motor 19, the change pay-out solenoid 21 and the vend motor 26. As pointed out heretofore, line L1 power exists at point "B." A circuit is, therefore, established from line L1 through conductor 245, closed contacts 169, 171 of the dime switch 35, conductor 268, through the dime relay 15, through conductors 264, 265, 244 to line L2. The coil 48 of the dime relay is, therefore, energized and armature 49 is drawn to the attracted position. This results in closing contacts 61, 62, closing contacts 63, 64, closing contacts 65, 66 and opening contacts 67, 68. Upon closure of contacts 61, 62 and 63, 64, the coil 69 of the quarter relay is energized by the following circuit; power from line L1 at "B" is conducted through conductors 245 and 276, closed contacts 132, 133, conductors 272, 266 and 267, through closed contacts 63, 64, through conductors 268, 271, through coil 69 of quarter relay 16 and through conductors 265, 244 to line L2. This results in opening contacts 83, 84, closing contacts 85, 86, closing contacts 87, 88, opening contacts 89, 91 and closing contacts 92, 93, all associated with the quarter relay 16. Opening of contacts 83, 84 deenergizes the dime and quarter blocking relay 18 so that no further dimes or quarters may pass through the coin chutes 36, 38, until the vending operation is completed, and at which time the quarter relay 16 is again deenergized.

The cam motor 19 is started by the following circuits being established; from conductor 245 at "B" where line L1 power exists, through conductor 273, closed contacts 128, 129 of cam switch 22, through conductor 273, closed contacts 87, 88 of the quarter relay, conductor 275, through the windings of cam motor 19, and through conductor 276a to point "C" where L2 power exists.

The cam motor is, therefore, started and, as best shown in Figures 11 to 13, as soon as the projection 122 is moved out of the notch 118, contacts 127 and 128 are closed. Contacts 129, 131 and 132, 133 of the cam switch 22 remain closed in this part of the cycle and do not open until the high point 120 of the cam contacts the projection 122 near the end of the cycle. When this occurs, contacts 129, 131 and 132, 133 open for a short period of time, but contacts 127, 128 remain closed until the projection 122 again drops into the notch 118.

The holding circuits for the dime and quarter relays 15 and 16, after the coin switch contacts 169, 171 have opened, are as follows; the holding circuit for the dime relay is from point "B" where line L1 power exists, through conductors 245, 276, through closed contacts 132, 133 of cam switch 22, through conductors 272, 266, through

closed contacts 61, 62 of the dime relay, through conductors 269, through coil 48 of the dime relay and through conductors 264, 265, 244, to line L2.

5 The holding circuit for the quarter relay is as follows; from point "B" where line L1 power exists, through conductors 245, 276, closed contacts 132, 133 of the cam switch 22, through conductors 272, 284 and 285, through closed contacts 85, 86 of the quarter relay, through conductor 271, through the coil 69 of the quarter relay and through conductors 265, 244 to line L2.

15 As soon as the coin opens contacts 169, 171, power from line L1 is then supplied by the following circuit to continue operation of the cam motor. Line L1 power from point "B" is conducted through conductors 245, 276, through closed contacts 129, 131 of cam switch 22, through conductor 273, closed contacts 87, 88 of the quarter relay, through conductor 275 of the cam motor 19, through the windings of the cam motor 19 to the conductor 276, which is connected at point "C" to L2 power. The motor, therefore, continues to run and, when the contacts 129, 131 and 132, 133 of cam switch 22 open near the end of the cycle, as shown in Figure 13, the dime and quarter relays 15 and 16 are deenergized and contacts 87, 88 of the quarter relay 16, therefore, open.

30 Power is then supplied to the motor to complete the cycle of the following circuit; from line L1 power at "B," through conductor 276, closed contacts 127, 128 of cam switch 22, through conductor 277, closed contacts 89, 91 of the quarter relay 16, through conductor 275, through cam motor windings to conductor 276 which is connected with line L2 power at point "C." As soon as the contacts 127, 128 of the cam switch 22 open, the motor is stopped, since the quarter relay 16 has already been deenergized and no circuit is established to continue operation of the motor with contacts 87, 88, 127, 128 open.

35 One coin in change is paid out by the pay-out solenoid 21 which is energized one time by the following circuit; from point "B" through conductors 245, 276, through closed contacts 129, 131 of the cam switch 22, through conductor 273, through closed contacts 65, 66 of the dime relay, through conductor 279, through the coil of the pay-out solenoid 21, through conductors 278, 276a to point "C" where line L2 power exists.

40 It is obvious, therefore, that as soon as the dime relay 15 is energized the pay-out solenoid 21 is energized and continues to be energized until contacts 132, 133 of cam switch 22 are opened at the end of the cycle of the cam motor 19. Although cam 116 is also being rotated and is consequently closing and opening contacts 141, 142, no power is supplied to the pay-out solenoid 21 because contacts 67, 68 of the dime switch are open.

45 In order to energize the vend relay 25, when a dime is used to thus operate the vend motor 26 through one vending cycle, the following circuits are established and the cam 116, driven by the cam motor 19, is affected to cause such energization. Power from point "B" is conducted through conductor 245, through closed contacts 169, 171 of the dime switch when closed by a coin, through conductors 268, 269, closed contacts 61, 62 of the dime relay 15, through conductors 266 and 284, closed contacts 92, 93 of the quarter relay 16, through conductor 286, through closed contacts 141, 142 and 143, 144 when closed

by rotation of the cam 116, through conductor 296, contacts 46, 47 of the drain switch 14, through conductors 293, 259 to one side of the vend relay coil 191 and through the vend relay coil 191 to conductors 261 and 262 which connect with L2 power at point "C." The vend relay 25 is, therefore, energized and the holding circuit of the circuit for operating the vend motor 26 is thereafter the same as described with respect to the nickel operation. Only one closing 10 of the contacts of switch 23 is required, although actually they close four times on each cycle.

When the limit switch contacts 208, 211 are opened by the cam 210 at the end of a vending cycle, the vend relay 25 and vend motor 26 are 15 deenergized as described above.

Quarter operation

When a quarter is inserted in the coin chute 38, contacts 175, 176 of the quarter switch 37 are momentarily closed. The quarter relay is, therefore, energized through the following circuit: from point "B" through conductor 245, closed coin switch contacts 175, 176, through conductor 282, through coil 69 of the quarter relay 16 and thence through conductors 265, 244 to line L2. In the quarter operation, only the quarter relay is energized and the dime relay is not energized. However, the circuit to the dime and quarter blocking relay 18 is broken because contacts 83, 84 of the quarter relay open until the quarter relay is deenergized near the end of the vending cycle. Therefore, it is impossible to have additional dimes or quarters operate the coin switches 35 and 37 until the vending cycle is substantially completed. This is because the blocking fingers 103 and 104 are blocking the chutes 36, 38.

The cam motor 19 is started by the following circuit being established from point "B"; through conductor 245, closed contacts 175, 176 of the coin switch 37, through conductors 282, 271, closed contacts 85, 86 of the quarter relay 16, conductors 285, 284 and 272, through closed contacts 132, 133 and 129, 131 of cam switch 22, through conductor 213, through closed contacts 87, 88 of the quarter relay 16, through conductor 275, to the cam motor and through conductor 276a, 244 to line L2. As soon as the cam motor starts, the contacts 127, 128 of the cam switch 22 are closed. The holding circuit for the quarter relay 16 is the same as described hereinbefore with respect to dime operation.

When the projection 122 on cam 115 is raised by the high point 120 near the end of the cycle, contacts 129, 131 and 132, 133 of cam switch 22 open, thus breaking the circuit to the quarter relay coil 69. Contacts 89 and 91 of the quarter relay 16 thereupon close and, since contacts 127, 128 of the cam switch 22 are closed at this time, the cam motor continues to operate until the projection 122 again drops into the notch 118.

Four nickels are given in change by operating the pay-out solenoid four times. This is accomplished by the following circuits, it being understood that the cam 116 is rotated one full revolution, so that the projections 135 and 135a thereon close contacts 141, 142 four times during one cycle. The circuit is from point "B" through conductors 245, 276, through closed contacts 132, 133 of cam switch 22, through conductors 272 and 284, through closed contacts 92, 93 of the quarter relay 16, through conductor 286, through contacts 141, 142 of the pay-out switch 23 when they are closed, through conductor 287, closed

5

contacts 67, 68 of the dime relay 15, through conductor 279, to the pay-out solenoid 21 and from the pay-out solenoid 21 through conductors 278, 276a and 244 to line L2.

The vend relay 25 and vend motor 26 are energized when a quarter is utilized, the following circuits being established; again, operation of the cam motor 19 and rotation of the cam 116 establish the necessary circuits. Closing of contacts 175, 176 completes a circuit through solenoid 69 by way of line 282, solenoid 69, lines 265, 244 to power line L2. When solenoid 69 is energized, a circuit is completed from point "B," lines 245, 276, contacts 132, 133, wire 284, contacts 92, 93, wire 286, contacts 141, 143, 144, contacts 44, 46, wires 293, 259, vend relay 25, conductors 261, 262 to point "C." Thereafter, the holding circuit and circuits for operating the vend motor 26 are the same as described with respect to the nickel operation.

When the vend motor 26 has completed a vending cycle, cam 210 operates limit switch 31 to deenergize the vend relay 25 and vend motor 26.

Drain switch circuit

A drain switch 14 may be provided so that if it is desired to empty the coin magazine 24 for any reason, or to provide a quick method of counting coins, the drain switch may be moved to the "drain" position shown in dotted lines in Figure 9 of the drawings. In the "drain" position, the cam motor operates continuously and the pay-out solenoid 21 is energized four times upon each revolution of the cam 116.

The drain operation is accomplished by the following circuits being established; first, the cam motor circuit is from point B through conductors 245 and 276, through closed contacts 132, 133 of the cam switch 22, through conductors 272, 295, through one set of the contacts 46, 47 of the drain switch, through conductor 294 to the cam motor and from the cam motor, through conductors 276a, 244 to line L2. As the motor continues to rotate, the contacts 132, 133 and 129, 131 will be open near the end of each cycle. However, the motor continues to operate because at that time contacts 127 and 128 of the cam switch 22 are closed and since the quarter relay 16 is not energized, contacts 89, 91 of the quarter relay are closed. A circuit, therefore, is established, which circuit is the same as described hereinbefore for continuing operation of the cam motor until the projection 122 drops into the notch 118. However, when the drain switch is being used, opening of contacts 127, 128 of the cam switch 22 does not stop operation of the motor because contacts 132, 133 are closed simultaneously with the opening of contacts 127, 128 and the circuit of the cam motor 19 is established.

The circuit for energizing the pay-out solenoid 21 four times upon each rotation of cam 116 is as follows; from point B through conductors 245, 276, through contacts 132, 133 of cam switch 22, conductors 295, 299, through one set of closed contacts 46, 47, through conductor 296, through contacts 143, 144 of pay-out switch 23, when closed, through conductor 287, through contacts 67, 68 of the dime relay 15, through conductor 279 to the pay-out solenoid 21 and back to line L2, through conductors 278, 276a and 244. It is apparent, therefore, that the cam motor 19 will operate continuously and four coins will be ejected on each revolution of the cam 116.

Nickel anti-jackpotting circuit

If a nickel sticks on the coin switch 33, or if

75

the contacts 164, 165 of the nickel switch remain closed for any reason, by the time a vending cycle is completed, the entire system is rendered inoperative by energization of the anti-jackpotting relay 27 which operates the latch 232 so that manual resetting is necessary. Obviously, energization of the anti-jackpotting relay 27 opens contacts 227, 228 so that the power supply from line L1 to substantially the entire system is immediately broken.

The circuit for energizing the anti-jackpotting relay 27 is as follows; through line L1, contacts 227, 228 of the anti-jackpotting relay 27, through conductors 252, 253, through contacts 217, 218 of the empty switch 32, through conductors 254, 246, through contacts 162, 165 of the nickel switch 33, through conductors 259, 263, through closed contacts 203, 204 of the vend relay 25 which are closed at this time because the vend relay is energized by the closure of the nickel switch 33, through conductor 289, through contacts 212, 213 of the limit switch which are closed by cam 210 at the end of the cycle, through conductor 291, through the coil 222 of the anti-jackpotting relay 27 and through conductors 292, 262, back to line L2 through conductor 244. The anti-jackpotting relay 27 is, therefore, energized and the power supply to the system is broken.

Upon energization of the anti-jackpotting relay 27, contacts 229, 231 thereof are closed. This lights the empty light 29, power being supplied from line L1 through closed contacts 229, 231, through the lamp 29 and through conductors 292, 262 and 244 back to line L2.

It is noted that when the power to the system is cut off by energization of the anti-jackpotting relay 27 that blocking relays 17 and 18 are both deenergized and block pins 100, 103 and 104 enter the coin chutes 34, 36, 38, respectively. Any coins that are inserted thereafter are returned through the return chute 42 until the apparatus is again placed in operative condition by opening nickel coin switch contacts 164, 165.

Dime anti-jackpotting circuit

If for any reason contacts 169, 171 and the dime switch 35 remain closed or if certain of the contacts of the dime and quarter relays remain closed when they should have opened, particularly if contacts 87, 88 and 89, 91 of the quarter relay are in an improper position, then the cam motor 19 will not complete a cycle and stops upon opening of contacts 132, 133 and 129, 131 of the cam switch 22. It is noted that as hereinbefore set forth, both the dime relay 15 and the quarter relay 16 are energized in the dime operation.

If the contacts 87, 88 are closed and contacts 89, 91 are open when the cam 15 opens contacts 129, 131 and 132, 133 of cam switch 22, no power may be supplied to the motor, even though contacts 127, 128 of the cam switch 22 are closed. Contacts 87, 88 are closed, but the fact that the other cam switch contacts are open does not permit power to be supplied to the cam motor 19. Furthermore, the circuit at that time is also broken to the pay-out solenoid 21, so that no further coins may be paid out.

In addition, the dime and quarter blocking relay 18 is deenergized because the quarter relay 16 is still energized and contacts 83, 84 are open. Therefore, it is impossible to operate dime or quarter coin switches 35 and 37, because the fingers 103, 104 block any further coins inserted.

and return them through the coin chute 42. In addition, contacts 108, 109 of block relay 18 are closed and the "five-cent only" lamp 28 will be illuminated. The circuit for accomplishing this is from the point of line L1 power at "A," through conductor 249, through the lamp 28, through conductor 301, through closed contacts 108, 109 of block relay 18 and through conductor 244 to line L2.

- 10 It will also be noted that if sufficient coins are not present in the magazine 24 to close contacts 149, 151 of the cam switch, block relay 18 is likewise deenergized, dimes and quarters are returned and the "five-cent only" lamp 25 will be illuminated because contacts 108, 109 are closed.

It is, therefore, impossible to obtain any further goods or services by dimes or quarters. It is also impossible to obtain any pay-out of change. However, the nickel chute is still clear, because the nickel blocking relay 17 is still energized; the vend relay 25 may be energized by a nickel to operate the vend motor 26.

- When the contacts 169, 171 of the dime switch are opened by the clearing of a coin, for example, 25 or the dime and quarter relay contacts return to their unenergized position, the cycle of the cam motor is completed because contacts 89, 91 of the quarter relay close and contacts 127, 128 of the cam switch 22 are already closed. The motor, 30 therefore, operates for a very short period of time and, when the projection 122 drops into the notch 118 of the cam 115, contacts 127, 128 of cam switch 22 open and the cam motor is deenergized. The system is then in condition for another vending cycle because dime and quarter block relay 18 is again energized by closure of contacts 83, 84 to remove fingers 103, 104 from the dime and quarter chutes and the pay-out solenoid 21 may be energized. Also, the contacts 108, 109 of block 40 relay 18 open and the "five-cent only" lamp 28 is extinguished.

Quarter anti-jackpotting operation

- If the contacts 175, 176 of the quarter switch 45 37 remain closed for any reason at the time a vending cycle is about to be completed or if the contacts of the quarter relay 16 remain in the energized position for any reason, the cam motor 19 does not complete a cycle and no further dimes 50 or quarters may be used to initiate a vending operation. No change is paid out and the "five-cent only" lamp is illuminated.

When the cam 115 reaches the position where the high point thereof opens contacts 129, 131 and 132, 133 of cam switch 22, the cam motor ceases to have energy supplied thereto because contacts 89, 91 of the quarter relay are open. The result is the same as that described with respect to the dime anti-jackpotting operation, 60 since the block relay 18 is deenergized and any further dimes and quarters must be manually returned. The power supply to the pay-out solenoid 21 is cut off and the "five-cent only" lamp 28 lights. Again, nickels may still be used to operate the vend relay 25 and the vend motor 26. Also, as soon as the contacts of the quarter switch 37 are open or the contacts of the quarter relay 16 return to their deenergized position, power is supplied to the motor because contacts 89, 91 of the quarter relay are closed and contacts 127, 128 of the cam switch 22 are also closed. The motor 19, therefore, completes its cycle and stops when the projection 122 drops into notch 118 and opens contacts 127, 128 of the cam switch 22.

From the above description, it will be apparent

that the goods or services to be vended are delivered upon the insertion of a coin, even though the coin sticks and in the event a dime or a quarter sticks, the goods or services are delivered and the proper change returned for that particular vending operation. Obviously, if a nickel sticks, the entire machine shuts down, but not until the vend relay has been energized and the vend motor 26 has completed a cycle and opens limit switch contacts 208, 211. Likewise, if a dime or quarter sticks, the cam motor 19 rotates the cams 115, 116 a sufficient distance to insure proper change being returned and, of course, the vend relay 25 is energized as soon as the coin switch contacts close. Thereafter, no dimes or quarters may be utilized but nickels may be used to obtain the goods or services.

From the foregoing, it will be apparent that I have provided a control for a vending machine and change maker which is completely foolproof, prevents jackpotting of goods or change, but insures the delivery of goods and/or change for any coin which is inserted and not returned.

Some changes may be made in the construction and arrangement of the parts of my device without departing from the real spirit and purpose of my invention, and it is my intention to cover by my claims any modified forms of structure or use of mechanical equivalents which may be reasonably included within their scope without sacrificing any of the advantages thereof.

I claim as my invention:

1. A change maker for vending apparatus, comprising a plurality of coin switch means, a plurality of coin operated members, one for each of said switch means, one of said coin operated members and corresponding switch means being responsive to a coin of single unit denomination, a second of said coin operated members and corresponding switch means being responsive to a coin of a multiple unit denomination, a third of said coin operated members and corresponding switch means being responsive to a coin of a greater multiple denomination than said second coin operated member and switch means, said coin operated switch means having an initial position and a position they are moved to responsive to coins operating said respective coin operated members, first and second electromagnetic relays, first and second switch means operated by respective relays, said relay switch means both having initial positions and positions to which they are moved in response to energization of said relays, an electric motor adapted to rotate continuously when energized, a circuit for energizing said electric motor upon movement of either both of said relays or said second relay only from said initial position, switch means operated by rotation of said electric motor, a source of power, means for establishing a circuit for energizing both of said relays upon said movement of said coin switch means corresponding to a coin of the lesser multiple unit denomination to operate its associated relay switch means, means for establishing a circuit for energizing said second relay only upon said movement of said coin switch means corresponding to the greater multiple unit denomination to operate its associated relay switch means, change pay out means, means for establishing a circuit for energizing said change pay out means upon operation of one of said relay switches and said motor operated switch means, and means for energizing said change pay out means a different predetermined number of times when both of said relays are

energized than when only said second relay is energized.

2. A change maker for vending apparatus, comprising a plurality of coin switch means, a plurality of coin operated members, one for each of said switch means, one of said coin operated members and corresponding switch means being responsive to a coin of single unit denomination, a second of said coin operated members and corresponding switch means being responsive to a coin of a multiple unit denomination, a third of said coin operated members and corresponding switch means being responsive to a coin of a greater multiple denomination than said second coin operated member and switch means, said coin operated switch means having an initial position and a position they are moved to responsive to coins operating said respective coin operated members, first and second electromagnetic relays, first and second switch means operated by respective relays, said relay switch means both having initial positions and positions to which they are moved in response to energization of said relays, an electric motor adapted to rotate continuously when energized, a circuit for energizing said electric motor upon movement of either both of said relays or said second relay only from said initial positions, first and second switch means operated by rotation of said electric motor, a source of power, means for establishing a circuit for energizing both of said relays upon said movement of said coin switch means corresponding to a coin of the lesser multiple unit denomination to operate its associated relay switch means, means for establishing a circuit for energizing said second relay only upon said movement of said coin switch means corresponding to the greater multiple unit denomination to operate its associated relay switch means, change pay out means, means for establishing a circuit including said second motor operated switch means and at least one of said relay operated switches for energizing said change pay out means upon operation of said motor operated switch means, means for energizing said change pay out means a different predetermined number of times when both of said relays are energized than when only said second relay is energized, said first motor operated switch means being effective to establish a circuit to maintain both of said relays energized when a coin of the lesser multiple unit denomination is utilized until the motor substantially completes its cycle and means for establishing a circuit for maintaining said second relay energized when a coin of the greater multiple unit denomination is utilized until the motor substantially completes its cycle.

3. A change maker for vending apparatus, comprising a plurality of coin switch means, a plurality of coin operated members, one for each of said switch means, one of said coin operated members and corresponding switch means being responsive to a coin of single unit denomination, a second of said coin operated members and corresponding switch means being responsive to a coin of a multiple unit denomination, a third of said coin operated members and corresponding switch means being responsive to a coin of a greater multiple denomination than said second coin operated member and switch means, said coin operated switch means having an initial position and a position they are moved to responsive to coins operating said respective coin operated members, first and second electromagnetic relays, first and second switch means operated by respective relays, said relay switch means both having initial positions and positions to which they are moved in response to energization of said relays, an electric motor adapted to rotate continuously when energized, a circuit for energizing said electric motor upon movement of either both of said relays or said second relay only from said initial position, switch means operated by rotation of said electric motor, a source of power, means for establishing a circuit for energizing both of said relays upon said movement of said coin switch means corresponding to a coin of the lesser multiple unit denomination to operate its associated relay switch means, means for establishing a circuit for energizing said second relay only upon said movement of said coin switch means corresponding to the greater multiple unit denomination to operate its associated relay switch means, change pay out means, means for establishing a circuit for energizing said change pay out means upon operation of one of said relay switches and said motor operated switch means, and means for energizing said change pay out means a different predetermined number of times when both of said relays are

erated by respective relays, said relay switch means both having initial positions and positions to which they are moved in response to energization of said relays, an electric motor adapted to rotate continuously when energized, a circuit for energizing said electric motor, upon movement of either both of said relays or said second relay only from said initial position, first and second switch means operated by rotation of said electric motor, a source of power, means for establishing a circuit for energizing both of said relays upon said movement of said coin switch means corresponding to a coin of the lesser multiple unit denomination to operate its associated relay switch means, means for establishing a circuit for energizing said second relay only upon said movement of said coin switch means corresponding to the greater multiple unit denomination to operate its associated relay switch means, change pay out means, means for establishing a circuit including said second motor operated switch means and at least one of said relay operated switches for energizing said change pay out means upon operation of said motor operated switch means, means for energizing said change pay out means a different predetermined number of times when both of said relays are energized than when only said second relay is energized, said first motor operated switch means being effective to establish a circuit to maintain both of said relays energized when a coin of the lesser multiple unit denomination is utilized until the motor substantially completes its cycle, means for establishing a circuit for maintaining said second relay energized when a coin of the greater multiple unit denomination is utilized until the motor substantially completes its cycle, and means for stopping the motor before it completes its cycle if either of said multiple unit denomination coin switches do not return to their initial position by the time the motor substantially completes its cycle or if said relay switches do not return to their initial position by the time the motor substantially completes its cycle.

4. A change maker for vending apparatus, comprising a plurality of coin switch means, a plurality of coin operated members, one for each of said switch means, one of said coin operated members and corresponding switch means being responsive to a coin of single unit denomination, a second of said coin operated members and corresponding switch means being responsive to a coin of a multiple unit denomination, a third of said coin operated members and corresponding switch means being responsive to a coin of a greater multiple denomination than said second coin operated member and switch means, a plurality of separate coin chutes for coins of each denomination having coin receiving openings positioned above the coin operated members, said coin operated switch means having an initial position and a position they are moved to responsive to coins operating said respective coin operated members, first and second electromagnetic relays, first and second switch means op-

erated by respective relays, said relay switch means both having initial positions and positions to which they are moved in response to energization of said relays, an electric motor adapted to rotate continuously when energized, a circuit for energizing said electric motor upon movement of either both of said relays or said second relay only from said initial position, switch means operated by rotation of said electric motor, a source of power, means for establishing a circuit for energizing both of said relays upon said movement of said coin switch means corresponding to a coin of the lesser multiple unit denomination to operate its associated relay switch means, means for establishing a circuit for energizing said second relay only upon said movement of said coin switch means corresponding to the greater multiple unit denomination to operate its associated relay switch means, a blocking relay normally energized from said source of power, a blocking member operated by said blocking relay and being capable of blocking coins passing through the coin chutes for coins of higher denomination, switch means controlled by said second electromagnetic relay and connected in circuit with said blocking relay, said blocking relay switch means being opened each time said second electromagnetic relay is energized, a vending relay adapted to actuate an article dispensing means, circuit connections controlled respectively by said switch for said single denomination coin operated member and by both of said electromagnetic relays for multiple denomination coins for independently and selectively energizing said vending relay, whereby coins of unit denomination may energize said vending relay when coins of multiple denomination are blocked by deenergization of said blocking relay, change pay out means, means for establishing a circuit for energizing said change pay out means upon operation of one of said relay switches and said motor operated switch means, and means for energizing said change pay out means a different predetermined number of times when both of said relays are energized than when only said second relay is energized.

MARVIN G. NELSEN.
